UNITED STATES PATENT OFFICE.

WILLIAM FRANCIS ALTENBAUGH, OF TIFFIN, OHIO.

ICE-TONGS.

SPECIFICATION forming part of Letters Patent No. 621,199, dated March 14, 1899.

Application filed August 23, 1898. Serial No. 689,322. (No model.)

To all whom it may concern:

Be it known that I, WILLIAM FRANCIS ALTENBAUGH, a citizen of the United States, residing at Tiffin, in the county of Seneca and 5 State of Ohio, have invented certain new and useful Improvements in Ice-Tongs, of which the following is a specification.

My invention relates to improvements in ice-tongs; and it consists of certain novel and 10 useful improvements in the construction of the same, fully disclosed in the specification following, and more particularly pointed out in the concluding claims.

In the drawing the figure represents the 15 tongs constructed in accordance with my invention and as used for handling a piece of ice.

The device consists of two arms or jaws 1 1, connected together at their upper ends by the 20 hinge 2. About mediately of the length of the jaws are rings or eyes 3 3, which I prefer to form by bending the jaws. A span of chain 4 connects these eyes 3 3 and forms the handhold or lift for the tongs. The length of the 25 chain 4 is sufficient to permit of a wide opening of the tongs, but must be less than the length of the tongs at the hinged end between the eyes 3 3 to give the gripping action to the tongs. At the lower ends the jaws are curved 30 inward and pointed to form the spurs 5 5.

In handling pieces of ice the tongs are held with the hinged end in the palm of the hand and the fingers grasping the span of chain. The spurs 5 5 are engaged with the ice, and 35 when the handhold-chain is pulled up against the weight of the ice the jaws will be pulled inward and firmly grasp the ice.

While I prefer to use a chain hand-lift grip, it is obvious that I may use rope or other flexible connection.

I claim—

1. The combination in gripping hand-tongs, of two jaws, each spurred at one end, and jointed each to the other at their other ends to form a hinge, and each provided with an eye at coincident points about mediately of their length, with a flexible means connecting the jaws from eye to eye and adapted to cause the jaws to grip with a force commensurate with the weight of the gripped article, the 45 jointed portion of the jaws and the flexible means forming a handhold.

2. Ice-tongs consisting of two hinged jaws bent to form spurs and bent to form coincident eyes at points about mediately of their 50 length in combination with a chain hand-lift grip connecting said jaws and adapted to cause the jaws to grip the ice with a force commensurate with the weight of the ice.

3. In a pair of gripping hand-tongs, the 55 combination with the jaws, each spurred at one end, and jointed each to the other at their other ends to form a hinge, and each provided with an eye at coincident points about mediately of their length, of a flexible means connecting the jaws from eye to eye and having a length less than the length of the jaws at their hinged ends from eye to eye, for the purpose stated, the jointed portion of the jaws and the flexible means forming a handhold. 65

4. As an article of manufacture, ice-tongs consisting of jaws hinged at their upper ends, bent to form spurs at their lower ends and bent at coincident points about mediately of their length to form eyes, and a chain handhold connecting the eyes.

WILLIAM FRANCIS ALTENBAUGH.
